United States Patent Office.

BENJAMIN J. HARRISON AND JAMES CONDIE, OF NEW YORK, N. Y.

Letters Patent No. 71,611, dated December 3, 1867.

IMPROVED FOLDING STEPS.

The Schedule referred to in these Letters Patent and making part of the same.

TO ALL WHOM IT MAY CONCERN:

Be it known that we, BENJAMIN J. HARRISON and JAMES CONDIE, of the city and State of New York, have invented, made, and applied to use, a certain new and useful Improvement in Folding Steps; and we do hereby declare the following to be a full, clear, and exact description of the said invention, reference being had to the annexed drawing, making part of this specification, wherein—

Figure 1 is a section of the said folding steps as open for use.

Figure 2 is a section through the top step and through one of the hollow columns connecting the side frames.

Figure 3 is an inverted plan of the top step; and

Figure 4 is an elevation of a pair of legs united by the cross-rail.

Similar marks of reference denote the same parts.

Folding steps have heretofore been made with side frames, carrying a top step secured by gluing, and nailing a moulding around the piece of wood, forming the top step, and gluing in blocks to secure the parts, similarly to the usual manner of connecting table-tops, and to the frame thus made a folding step has been applied that can be inverted into the said frame or turned down for use.

These folding steps are convenient for domestic use, but they are bulky, and very costly in transportation. The steps require to be boxed, and the freight is charged on them as furniture, and because of the liability to injury in transportation, the rate of freight is much higher than on most other kinds of goods. The consequence has been that the convenient article of folding steps has been confined in its use almost entirely to places near to the manufactory.

The nature of our said invention consists in folding steps formed with a removable top, constructed in such a manner as to be easily separated from the frame, but firm when applied in its place with a frame, that is, tied together by hollow columns and bolts, and with swinging steps that can be taken apart or put together with facility. By this construction we are enabled to pack the folding steps into about one-sixth the space occupied by them when put together, and thereby effect considerable saving in the bulk, but also in the rate of charges for freight, because the parts of the steps when disconnected are not liable to be broken. Besides this, the steps when put together are much stronger and more durable; at the same time, the cost of manufacture is but little increased.

In the drawing, *a a* are the vertical legs, united in pairs by the cross-rails *b b*. At the top of each leg is a circular tenon, *c*, and *d* is the top step, formed with a surrounding base, *e*, that is mortised and tenoned together at the angles, and bored with a hole at the points of intersection for receiving the tenon *c*, so that the base is made very strong by its own mortises and tenons at the angles, and these, in addition to gluing, are held together by the tenon *c* passing into them. The base *e* is arched upwards between the angles so as to lessen the weight. We provide the tubular columns *f* of a length to pass between the frames formed of the legs *a* and cross-pieces *b*, and the ends of these columns are to be steadied by passing into recesses in the inner surfaces of the said frames. The bolts *i*, with heads and nuts at their respective ends, pass through the frames, and through these columns *f*, and secure the parts in the most rigid manner. The steps *k k* are of a width to pass in between the frames *a*, and are secured to the side pieces *l* by screws so as to be easily connected or disconnected, and *m* is a tie-rod, on which they can be swung over into the position shown by red lines, or supported when in the position shown by black lines, fig. 1.

It will now be understood that these folding steps can be prepared for putting together, and then packed into a small compass for transportation, and put together with great facility at their destination, or the steps can be taken apart and packed after they have been once put together, it only being necessary to take out the rod *m*, turn the frame *a* upside down, and pull the legs or knock the step *d* and its base *e* off the tenons *c*, and then loosen the bolts *i*, and separate the columns and frames. The parts can then be packed together in a very compact mass in a small space.

What we claim, and desire to secure by Letters Patent, is—

The folding steps constructed in the manner and for the purposes specified.

In witness whereof we have hereunto set our signatures, this sixteenth day of August, 1867.

BENJ. J. HARRISON,
JAMES CONDIE.
